UNITED STATES PATENT OFFICE

96,593

DESIGN FOR AN EMBOSSED TRANSPARENT PAPER OR SIMILAR MATERIAL

Kathleen Coe, Springfield, Mass., assignor to Westfield River Paper Company Inc., Russell,
Mass., a corporation of Massachusetts

Application June 24, 1935, Serial No. 57,392

Term of patent 14 years

To all whom it may concern:

Be it known that I, Kathleen Coe, a citizen of the United States, residing at Springfield, county of Hampden, State of Massachusetts, have invented a new, original, and ornamental Design for an Embossed Transparent Paper or Similar Material, of which the following is a specification, reference being had to the accompanying drawing forming a part thereof, which is a plan view of a piece of embossed transparent paper, enlarged approximately three times the actual size, embodying my design and showing several repeats.

I claim:

The ornamental design for an embossed transparent paper or similar material, as shown and described.

KATHLEEN COE.
